[57] **CLAIM**

The ornamental design for mount for towel holder, as shown and described.

DESCRIPTION

FIG. 1 is a perspective view of a mount for towel holder showing the first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of the second embodiment thereof, with the broken-line disclosure of a towel bar being for illustrative purposes only and forming no part of the claimed design; and,

FIG. 9 is a perspective view of the first embodiment thereof, with the broken-line disclosure of a towel ring being for illustrative purposes only and forming no part of the claimed design.
